UNITED STATES PATENT OFFICE.

GEORGE N. TODD, OF FORT SMITH, ARKANSAS.

COTTON-HARVESTER.

SPECIFICATION forming part of Letters Patent No. 295,463, dated March 18, 1884.

Application filed July 26, 1883. (No model.)

To all whom it may concern:

Be it known that I, GEORGE N. TODD, a citizen of the United States, residing at Fort Smith, in the county of Sebastian and State of Arkansas, have invented certain new and useful Improvements in Cotton-Pickers, of which the following is a specification, reference being had therein to the accompanying drawings.

My invention relates to improvements in cotton-harvesting machines; and it consists in certain constructions and details of construction hereinafter pointed out and claimed.

The object of my invention is to produce an improved machine which operates to pick and deliver cotton by means of endless belts provided with teeth somewhat similar to the teeth of a carding-engine.

In the drawings forming part of this specification, Figure 1 is a perspective view of the frame of the machine with the operative parts removed. Fig. 2 is a diagonal front view, looking into the picker. Fig. 3 is a side view of the machine, parts being broken away. Fig. 4 is a rear view, the rear plate being removed 25 on the left-hand side, to show the belts and driving-cylinders in position. The right-hand side of the figure shows the gearing by which the belts are driven.

A denotes the frame of the machine. This frame is mounted on wheels, the driving-wheels being on axles 1. The frame carries the operative parts of the machine which are driven from the said wheels. The frame is composed of wood or metal, and has a converging passage-way through from front to rear. The front part of the frame is partially closed by plates A', one at each side. The plates have spaces B extending in a horizontal direction, or nearly so, from the opening in the middle 35 of the frame toward the sides or corners of the machine. Between the spaces B the arms or projections B' are arranged, as shown, to form bearings for the ends of the cylinders which carry the picker-belts. The top of the frame has side passages, E, for the carrier-belts, and suitable braces, as F, extending diagonally from the end pieces, D, and may have braces G at the sides. It must be understood, however, that I do not limit myself 50 to this particular form of frame and braces.

Extending in front of the frame A are suitable

supports, which carry standards a; or the sides of the frame may project forward and terminate in said standards. From these standards fingers or guides a' extend to the 55 projections B'. These fingers or guides are of triangular, conical, or wedge form, being nearly pointed in front and growing gradually wider and thicker toward the rear. The fingers may be made of bent sheets of metal, or 60 of any light material, presenting the rounded edge toward the inside passage-way. They serve to enter between the branches of the cotton-plant, and guide said branches into the spaces between the picker-belts. The projections B' on the plates at the rear of the frame serve as supports for the picker-belt cylinder.

Extending from the projections B' at the front of the machine to similar projections at the rear are cylinders or cones b b'. These 70 cylinders, if cylinders are used, carry sprocket-wheels at each end for the purpose of driving endless belts. The rear ends of the cylinders b b' are nearer to the center of the machine than the front ends, and the cylinders 75 may be inclined with reference to the frame of the machine, and also with reference to each other.

Surrounding the cylinders b b' are endless belts c, of textile or similar material, carrying 80 pickers c'. These endless belts are preferably of the material similar to that used in covering card-clothed rolls in carding-machines, but are in some respects peculiar. I prefer the endless belts to be made of rubber webbing as improved by me for this purpose.

It is not absolutely essential that the endless picker-belts shall be on rolls nearly parallel to the sides of the machine. They may be mounted on transverse rolls, so that one 90 edge of each belt will be toward the passage-way in the middle of the machine, the belts being adapted to enter between the branches of the plant, as before stated. The construction last referred to, however, I do not claim 95 herein, but may make the subject of a separate application.

Back of the cylinders or cones b', and parallel with the outside surface thereof, there is an endless belt, m, of fabric of the nature of card-clothing, similar to that of belts c. This belt is as wide as the belts c are long, and near

enough to said belts so that the teeth of belt *m* barely pass those of belts *c*. The belt *m* is carried on cylinders *n*, one near the top and the other near the bottom of the frame, and 5 standing in such relation with the frame that they are parallel to a plane perpendicular to the outside of all the rolls *b*. The belt *m* is driven by sprocket-wheels *o* at the end of cylinders *n*. It is further sustained by idler-cylinders *P*, arranged, preferably, at about equal 10 intervals between the rolls *b*. The belt *m* will thus be allowed to give slightly at points opposite the belts *c*, but will be held in general proximity thereto. The belt *m*, I call the 15 "stripper" and "cleaning" belt. Its direction of motion is preferably downward on the inside and upward on the outside, so as to strip the cotton from belts *c*, carry it to the bottom of the frame, and elevate it again on 20 the side away from the picker-belts *c*. The teeth on this belt will be curved in the direction of their movement. The picker-belts *c* and the stripper-belts *m* are preferably strengthened and carried at the edges by chains, 25 straps, or metallic bands perforated for the passage of the teeth on the sprocket-wheels.

Parallel with the outside of the stripper-belts *m*, I arrange a screen, *m'*, preferably of canvas. There is a little space between the 30 belt *m* and the canvas *m'*, and the cotton is carried up in this space by motion of belt *m*.

At the top of the belt *m* there is a rapidly-revolving wiper or beater, *Q*, which is geared preferably from the shaft *n*, which drives belt 35 *m*, as shown at 23, Fig. 3. This wiper has arms like the arms or vanes of a wind-wheel, which travel in the same direction as the belt *m*, but at a much higher speed. These arms engage the fiber on the stripper-belt and throw 40 it from the ends of the bent teeth, so that it falls upon the carrier-belt *R*.

The carrier or conveyer belt *R* moves in ways or passages *E* in the frame of the machine. It is carried by two pulleys, *S*—one 45 at each end of the frame—one of which may be on shaft *K*, and be driven by a belt or chain, *V*, from the hub *X* of the driving-wheels. The cotton, which is thrown by the wipers *Q* upon the belt *R*, is carried by said belt back to 50 ward the scraper *U*, which is placed just above the surface of belt *R* on which the cotton rides, and is set at an incline thereto, so that as the belt moves back the cotton will be scraped from its surface into the sack or other receptacle *V'*, which is preferably near the rear of the machine. The cylinders *b* are driven by an arrangement of bevel-gears *e* on shaft 55 *f* engaging one with each bevel-gear *g* on the shafts *b* or *b'*. The shaft *f* derives its motion from bevel-gears *h*—the latter on shaft *K*—and shaft *K* is driven by chain *V*, as stated. The shaft also serves to drive shaft *n* of the stripper-belt by means of bevel-gears 60 *5* *6*, connecting the said shafts.

65 The operation of my device is as follows: The frame is mounted at such a height as to

run along a little above the surface of the ground, and is drawn along the rows of cotton in such manner as to straddle the row which is to be picked. The fingers *a'* guide 70 the plants toward the front opening in the frame and at the same time enter between the branches of the plant, hold the branches apart, and guide them into the apertures *B* in the frame. As soon as the frame passes over the 75 plant, so that the branches are inside of the front plates, *A'*, the endless belts, which are in constant motion, begin to comb the cotton fiber from the plant. As the belts converge toward the rear of the machine the branches 80 are more and more compressed between the belts, and are thus thoroughly exposed to the combing action of the teeth on the endless belts. The fiber from the plants is taken by the teeth on the endless picker-belts and 85 conveyed toward the outer frame of the machine, the picker-belts being driven, preferably, in the direction shown by the arrows, Fig. 2. As the teeth of the picker-belts are very close together, they have little or no effect on the 90 leaves, branches, or trash from the cotton-plants. The same remain attached to the stalk, and the machine passes over and leaves the plants, having picked off the fiber. The stripper-belt takes the fiber from all the picker- 95 belts on one side and carries it down toward the bottom of the machine, and then up between the belt and outside screen. This arrangement is for convenience, as the delivery need not necessarily be at the top of the 100 machine. Arriving at the point of delivery from the stripper-belt, (by preference the top of the machine, as stated,) the rotary beater takes the fiber from the stripper and throws it on the conveyer-belt, by which it is carried to the 105 bag or receptacle.

I claim—

1. In a cotton-picking machine, in combination with suitable driving mechanism, a series of horizontal cylinders extending lengthwise 110 of the machine, or nearly so, and a series of endless belts arranged on said cylinders so as to pass between the branches of the plant, substantially as described.

2. The combination of the supporting-frame, 115 two series of horizontal cylinders extending lengthwise of said frame, or nearly so, with a passage-way between them, endless picker-belts arranged on the cylinders, substantially as described, and suitable driving mechanism, 120 all substantially as shown and set forth.

3. The combination, with the front plates having spaces therein, as described, of the guide-fingers, arranged to guide the branches of the plant into said spaces. 125

4. The combination, with the plates *A'*, having spaces *B* therein, of the guide-fingers *a'* in front of projections *B'*, said guide-fingers being pointed in front, and gradually increasing in breadth and thickness toward projections *B'*, as shown and described. 130

5. The combination, with the frame having

- front plates, A', provided with projections, as stated, of the guide-fingers of the form described, arranged in front of said projections, and the cylinders journaled in said projections 5 and carrying endless picker-belts, substantially as described, and for the purpose stated.
6. The combination, with a series of endless picker-belts and suitable operating mechanism, of stripper-belt arranged, as described, 10 in proximity to the picker-belts, so as to strip and convey the cotton therefrom, substantially as described.
7. The combination, with a series of picker-belts arranged horizontally, or nearly so, and 15 operating mechanism, substantially as described, of a stripper-belt arranged in proximity thereto, and adapted to strip and convey the cotton therefrom by suitable mechanism, substantially as stated.
- 20 8. The combination, with the series of picker-belts, arranged as described, of a stripper-belt arranged in proximity thereto, as stated, and a screen arranged parallel with one face of the

stripper-belt, whereby the cotton may be stripped from the picker-belts and carried between the stripper-belt and the screen to a point of delivery, substantially as stated. 25

9. The combination of a series of picker-belts, arranged as described, the stripper-belt and screen, and a revolving wiper, all arranged with reference to each other, substantially as set forth. 30

10. The combination of the stripper-belt, the rotating wiper, and the carrier-belt, all arranged and operating as set forth. 35

11. The combination of the stripper-belt, the revolving wiper, the conveyer-belt, and the scraper arranged, as described, to scrape the cotton from the conveyer-belt into a suitable receptacle, substantially as described. 40

In testimony whereof I affix my signature in presence of two witnesses.
